ART OF REFINING

Willis S. Gullette, Highland, Ind., assignor to Sinclair Refining Company, New York, N. Y., a corporation of Maine

Application May 8, 1935, Serial No. 20,309

2 Claims. (Cl. 196—36)

This invention relates to improvements in operations combining a fractionating operation and a vapor phase refining operation in which the vapor mixture from the fractionating operation is subjected, while still predominantly in the vapor phase, to refining treatment. The invention relates more particularly to improvements in the control of the fractionating operation in such combined operations. The invention includes apparatus for carrying out the process as well as the process.

The invention has been found to be of special value and application in connection with operations in which complex hydrocarbon vapor mixtures, produced for example from petroleum stocks, are subjected to fractionation accurately to separate higher boiling constituents from a vapor mixture condensing to form a distillate product of the desired boiling range and in which this vapor mixture, before condensation, is subjected to refining treatment in vapor phase. Operations embodying this general scheme of operation have long been known and practiced. The so-called "Gray process" and the so-called "Lachman process" for example, both refining operations applied to hydrocarbon mixtures in vapor phase, have been applied to the vapor mixture from an immediately preceding fractionating operation. In such operations as hitherto conducted, however, difficulties arising with respect to control of the fractionating operation have involved some compromise with respect to either the efficiency of the combined operation, the accuracy of the fractionation as reflected in the final product or both.

For example, the fractionating operation is sometimes controlled by returning to the fractionating operation as a refluxing medium a part of the final product condensed following the refining operation, the total vapor mixture from the fractionating operation being subjected to the refining operation. Using this scheme of control, the lag through the refining operation so affects the characteristics of the final condensate that it is not effective accurately to control the separation between higher boiling constituents and constituents suitable as components of the vapor mixture separated in the fractionating operation. Consequent failure of accurate fractionation tends to overload the refining operation and thus to impair its efficiency, or alternatively to require the use of a refining system disproportionately large with respect to the net make of the final product. Further the vapor mixture from the refining operation is sometimes sub-

jected to another fractionating operation, for example in connection with the so-called Gray process to separate higher boiling polymers produced by the refining operation, before final condensation. Return of part of the final condensate to the fractionating operation preceding the refining operation in such a combined operation multiplies the difficulties of control, and overloads the subsequent fractionating operation as well as the refining operation or alternatively requires the use of a fractionating system following the refining operation disproportionately large with respect to the net make of the final product. Again for example, the fractionating operation preceding the refining operation is sometimes controlled by returning to the fractionating operation as a refluxing medium a condensate produced by passing the total vapor mixture from the fractionating operation from a partial condenser before it reaches the refining operation. This scheme of control is subject to a very serious disadvantage in that it dissipates part of the contained heat of the vapor mixture flowing to the refining operation, heat which is usually necessary and almost invariably advantageous if the refining operation is to be conducted efficiently and economically.

This invention provides a process and apparatus for controlling the fractionating operation in such operations combining a subsequent vapor phase refining operation with the fractionating operation which, avoiding such difficulties, affords accurate and easy control of the fractionating operation without impairing the efficiency of the refining operation and without requiring the refining operation, and any subsequent fractionating operation, to handle more than the net make of the final product.

According to this invention, the gross vapor mixture from the fractionating operation preceding the refining operation is divided into two streams of the same composition, one of these streams is subjected to the refining operation and the vapor mixture from the refining operation is condensed, either with or without further fractionation, to form the final product, and the other of these streams is directly condensed and the condensate so produced is returned to the fractionating operation preceding the refining operation as a refluxing medium. It will be immediately apparent that the practice of this invention does not require any recirculation through the refining operation, and any subsequent fractionating operation, of any part of the final product. The fractionating operation preceding the refin-

ing operation is accurately and easily controlled by regulating the rate at which this refluxing medium, the total condensate of an untreated part of the total vapor mixture from the fractionating operation, is returned to this fractionating operation. This condensate being strictly an aliquot part of the vapor mixture separated in the fractionating operation, is well adapted to effect accurate separation of higher boiling constituents from the vapor mixture separated in the fractionating operation.

The division of the gross vapor mixture from the fractionating operation is with advantage controlled by controlling the discharge of condensate from the condenser through which that part of this vapor mixture condensed to be returned as reflux condensate passes, for example to maintain a sufficient supply of refluxing medium to meet the requirements, within the limits of variation for the particular operation, in a particular operation. By so controlling the division of the gross vapor mixture, any surges or similar disturbances within the system incident to variations in this division of the gross vapor mixture from the fractionating operation which might otherwise interfere with the regularity of operation are eliminated or reduced to a minimum.

The invention will be further described in connection with the accompanying drawing which illustrates one form of apparatus embodying the invention and adapted for carrying out the process of the invention. It will be understood that the accompanying drawing is diagrammatic and conventional and somewhat in the nature of a flow chart.

In the apparatus illustrated, a vapor mixture from a still or other source enters the fractionating tower 1 through vapor connection 2. Higher boiling components separated as a condensate in the fractionating tower are discharged through liquid connection 3 and the fraction from which these higher boiling components are separated escapes through vapor connection 4. Vapor connection 4 divides into two branches, one branch 4a communicating with condenser 5 and the other branch 4b communicating with refining tower 6. The vapor mixture from the refining tower passes to condenser 7 through connection 8 and the condensate from condenser 7 is discharged through connection 9 into receiver 10. The final product, fractionated and refined, is discharged from receiver 10 through connection 11. Condensate from condenser 5 is discharged into accumulator 12 through liquid connection 13. Condensate from the accumulator 12 is returned to the fractionating tower 1 as a refluxing medium through connection 14 by means of pump 15. Connection 13 includes a valve 16 arranged to be operated by a flow-controlled mechanism 17 to maintain an approximately constant level in the accumulator 12, that is the valve 16 is automatically controlled to open as the level in the accumulator 12 falls and to close as this level rises. Gas separating in the receiver 10 is discharged through connection 18. Gas separating in the accumulator 12 may be discharged either through a separate connection 19 or, by means of by-pass 20, through the connection 18 with gas from the receiver 10, if the condenser 5 is designed to provide the pressure drop

lower than the pressure drop through the refining tower 6 and the condenser 7. Extra gas from the receiver 10 and from the accumulator 12 is discharged through a common line, 18 in the apparatus illustrated, a single valve in this line, 21 in the apparatus illustrated, can be used to maintain and control any pressure in the system.

In carrying out the process of the invention in the illustrated apparatus, the fractionating operation conducted in the tower 1 is controlled by regulated return, through connection 14, of the condensate constituting the refluxing medium collected in accumulator 12. The return of this refluxing medium may be controlled manually or automatically, for example to maintain a predetermined temperature at the top of the fractionating tower 1. The gross vapor mixture escaping from the fractionating operation through connection 4 is divided into two streams of the same composition, one passing to the refining operation conducted in the tower 6 through connection 4b and the other passing to the condenser 5 through connection 4a. That part of this vapor mixture passing to the condenser 5 is condensed to form the refluxing medium collecting in accumulator 12. This part of the vapor mixture is not subjected to and does not burden the refining operation conducted in tower 6, or any subsequent fractionating operation which may be included. The other part of the vapor mixture from the fractionating operation is subjected to the refining operation to become, when condensed, the final product collected in receiver 10. No part of this final product need be recirculated through the refining operation in controlling the fractionating operation conducted in tower 1 in accordance with this invention.

I claim:

1. In an operation combining a fractionating operation and a vapor phase refining operation applied to the vapor mixture from the fractionating operation, the improvement in controlling the fractionating operation which comprises dividing the gross vapor mixture from the fractionating operation into two streams of the same composition, subjecting one of these streams to the refining operation, condensing the other stream and returning the condensate so produced to the fractionating operation as a refluxing medium, and controlling the division of the gross vapor mixture by controlling directly the discharge of condensate from said condensing operation.

2. In combination, a fractionating tower, a vapor phase refining tower, a condenser and an accumulator, a vapor connection between the fractionating tower and the refining tower and a vapor connection, taking a vapor mixture of the same composition as the first-mentioned vapor connection from the fractionating tower, between the fractionating tower and the condenser, a liquid connection between the condenser and the accumulator and means for returning condensate from the accumulator to the fractionating tower as a refluxing medium, a valve in said liquid connection, and means responsive to changes in liquid level in the accumulator controlling said valve to maintain an approximately constant level therein.
